Primary Examiner — David Muller

CLAIM

The ornamental design for a positioning device for eye drop bottles, as shown and described.

DESCRIPTION

FIG. 1 is a perspective view of a positioning device for eye drop bottles showing my new design;

FIG. 2 is a front view thereof; the rear view being a mirror image;

FIG. 3 is a side view thereof; the opposite side view being a mirror image;

FIG. 4 is a top view thereof;

FIG. 5 is a bottom view thereof; and,

FIG. 6 is a cross-sectional view thereof taken along line 6-6 in FIG. 5.
